UNITED STATES PATENT OFFICE.

JAMES FRANCIS ROWLEY, OF CHICAGO, ILLINOIS.

HINGE-JOINT FOR ARTIFICIAL LIMBS.

1,269,004.

Specification of Letters Patent. Patented June 11, 1913.

Application filed June 18, 1917. Serial No. 175,386.

To all whom it may concern:

Be it known that I, JAMES F. ROWLEY, a citizen of the United State of America, and a resident of Chicago, county of Cook, 5 and State of Illinois, have invented certain new and useful Improvements in Hinge-Joints for Artificial Limbs, of which the following is a specification.

This invention relates to ball bearing 10 joints of the general nature shown in applicant's Patent No. 1,123,928, ankle joints for artificial limbs, but the present device is arranged with particular reference to the requirements for knee-joints.

15 The main objects of the invention are to provide a ball bearing joint which is light and strong, and having small dimensions, free from projecting parts and permitting a steady, easy action of the joint; to provide 20 a ball bearing joint of this nature of minimum axial dimension; and to provide a hinge joint for artificial limbs which is readily reversible for application to either the right or left sides of the limb.

25 An illustrative embodiment of this invention is shown in the accompanying drawings, in which—

Figure 1 is a side elevation of the bearing as employed in a knee-joint for an artificial 30 limb.

Fig. 2 is an edge view.

Fig. 3 is an enlarged section on the line A—A of Fig. 1.

Fig. 4 is a plan view of one of the bearing 35 members.

Ball bearings are utilized in the present device, not for the usual purpose of reducing friction, but to produce a joint wherein, due to the rolling action of the bearing, the 40 lack of lubrication will not interfere with its desired action or produce sound. It is also preferable, particularly when the amputation is below the knee, that a joint of this nature should not be bulky, and it 45 should be adjustable for the purpose of permanently regulating the pressure between the bearings and thus maintaining the desired action.

In the drawings, the member 1 is suitably 50 formed for attachment to the lower leg section of an artificial limb, the front of the leg being to the left in this figure. This member is in the form of a brace of elliptical cross section and is provided with drilled 55 apertures 2 for receiving the screws by

which the strap or brace is secured to the lower leg section.

The head 3 of the brace 1 is offset from the longitudinal center line of the brace and is of the proper thickness to be straddled by 60 the forked end of a member 4 which is adapted to be attached to the thigh section of the limb. Adjacent to the forked portions 5 and 6 of the member 4, the brace 1 is somewhat enlarged to provide a curved 65 surface flush with the surfaces of the forked portions 5 and 6 and also to provide shoulders 18 for engagement with the forward edge of the member 4 to limit the forward motion of the lower leg section around the 70 joint.

The head 3 of the member 1 is provided with an annular bearing race 7 adapted to carry a plurality of balls 8. The arm or branch 5 of the member 4 is provided with an annular recess 9 on the inner side thereof, adapted to receive and support a bearing cone 10 which is provided with a central aperture 11 which registers with a threaded aperture 12 in the branch 5. The 75 branch 6 of the member 4 is provided with a centrally located cylindrical aperture 13 adapted to tightly receive the cylindrical head 14 of a screw 15 which passes through the aperture 11 in the cone 10 and has 80 threaded connection with the threaded aperture 12 in the arm 5. The head 14 is provided with a conical bearing surface 16 which is in opposed relation to the bearing surface of the cone 10, and together with 85 said cone forms a split bearing race which coacts with the balls 8 and is in opposed relation to the annular ball race 7 in the member 3. The head 14 of the screw 15 is provided with a pair of apertures 17 adapted 90 to receive a spanner wrench for adjusting the screw 15.

The bearing is assembled by sliding the head 3 of the member 1 between the branches 5 and 6 of the member 4. The bearing cone 10 is then dropped through the aperture 13 in the member 6 into the recess 9 in the member 5, thus locking the head 3 between the branches 5 and 6. The balls 8 are then dropped into place, said balls being held in the annular ball race 7 of the member 3 by the inclined surface of the bearing cone 10. The screw 15 is then passed through the aperture 11 in the cone 10 and threaded into engagement with the 110

branch 5 of the member 5. The head 14 of the screw 15 is adjusted so that the conical bearing surface 16 thereof will coact with the balls 8 and thus form, together with the cone 10, a split ball race which is in opposed relation to the annular bearing race 7. Adjustment of the screw 15 is secured by means of a spanner wrench engaging the apertures 17 in the head 14.

10 The pressure between the members 1 and 4 through the balls 8 may be regulated by an adjustment of the screw 15, otherwise no direct contact between these members along the surfaces 19 and 20 is necessary. In practice, it is found that by having the bearing cone 10 freely rotatable within its seat 9, once the device is adjusted, continued use of the joint does not affect such adjustment or rotation of the screw 15. The member 15 4 is reversible with respect to the member 1, thus providing a knee-joint which can be used interchangeably on either the right or left side of an artificial limb. The device is 20 reversible by turning the member 4 with respect to the member 1 and bending the latter member in the opposite direction to that in which it is shown bent in Fig. 2. The bearing 25 is suitable for elbow joints for artificial arms, in substantially the form shown in 30 the drawings.

Another advantage of this construction is that the bearing cone 10 is not threaded on the shank of the screw 15, but is loosely seated with respect thereto and with respect to the arm 5, and it is thereby self-aligning. Imperfections in the construction 35 of the different bearing races are taken care of by this loosely mounted, self-aligning cone in such manner that the balls 8 will bear 40 equally against their respective ball races.

Although but one specific embodiment of the invention has been herein shown and described, it will be understood that numerous details of the construction shown may be 45 altered or omitted without departing from the spirit of the invention as defined by the following claims.

I claim:

1. A hinge joint for artificial limbs, comprising a pair of members which are formed to interfit at one end by one member being forked to straddle the other, a ball race formed in the unforked one of said members, and a pair of bearing cones supported 50 in said forked member, one of said bearing cones having a shank threaded into one arm of said forked member and a cylindrical head fitting a cylindrical aperture in the remaining arm of said forked member.

60 2. A hinge joint for artificial limbs, com-

prising a member having a bearing race therein, a second member having a bifurcated head, the branches of said head being adapted to embrace the opposite sides of said first-mentioned member, one of said 65 branches having a recess therein, a bearing cone loosely carried in said recess, a second bearing cone supported by the other of said branches and having threaded relation with said one branch, said cones having their 70 bearing surfaces in opposed relation to each other and forming a split bearing race located in opposed relation to the bearing race in said first-mentioned member, and rollers coacting between said bearing races. 75

3. A hinge joint for artificial limbs, comprising a pair of members which are formed to interfit at one end, a ball race formed in one of said members, a stud mounted on one of said members and passing through 80 the other of said members so as to hold said members together, a loosely mounted bearing cone surrounding said stud, and rollers coacting with said bearing cone and ball race. 85

4. A hinge joint for artificial limbs, comprising a pair of members which are formed to interfit at one end by one member being forked to straddle the other, a ball race formed in the unforked one of said members, and a pair of bearing cones supported 90 by said forked member, one of said bearing cones being supported by one arm of said forked member and having an aperture therethrough, and the other of said cones having a head supported by the other arm 95 of said forked member and a shank extending through the aperture in said one cone and directly connected to said first-mentioned one arm.

5. A joint for artificial limbs, comprising 100 a pair of members one of which is forked to receive the other in hinge relation, said members being apertured in coaxial alignment with the hinge axis and provided with ball races respectively, balls coacting with 105 said races, the race for the forked member being split and including a part set in and projecting from the inner face of one of the fork arms, and a part having a head held in the aperture of the opposite arm and a 110 shank extending through the first mentioned part and supported in the aperture of the said one arm, and means for adjusting the spacing of said parts, the aperture in said opposite arm being adapted to admit both 115 of said parts in assembling the joint.

Signed at Chicago this 14th day of June, 1917.

JAMES FRANCIS ROWLEY.
